UNITED STATES PATENT OFFICE.

JULES J. SARRAZIN, OF NEW ORLEANS, LOUISIANA.

DESIGN FOR A HANDLE FOR TOOTH-BRUSHES.

45,572.

Specification for Design.

Patented Apr. 7, 1914.

Application filed December 22, 1913. Serial No. 808,288. Term of patent 14 years.

To all whom it may concern:

Be it known that I, JULES J. SARRAZIN, a citizen of the United States, residing at New Orleans, in the parish of Orleans and State of Louisiana, have invented a new, original, and ornamental Design for Handles for Tooth-Brushes, of which the following is a specification, reference being had to the accompanying drawing, forming a part thereof, in which a perspective view of the design is shown.

I claim:

The ornamental design for a handle for tooth brushes, as shown.

In testimony whereof I affix my signature, in the presence of two witnesses.

JULES J. SARRAZIN.

Witnesses:

M. J. HOWARD,
CHARLES SHEPARD TULLER.
